(57) **ABSTRACT**

The present invention relates to a trampoline with adjustable elasticity. The trampoline includes several corresponding trampoline ring parts, and adjacent trampoline ring parts are connected through a joint to form the trampoline; and an arc length between the adjacent trampoline ring parts changes through adjustment of the joint, and is fixed after relative positions of the two adjacent trampoline ring parts are properly adjusted. The elasticity of the trampoline of the present invention is adjustable, thereby providing a user with an exercise experience of a variety of elasticity.

**TRAMPOLINE WITH ADJUSTABLE
ELASTICITY**

BACKGROUND

Technical Field

The present invention relates to a trampoline with adjustable elasticity.

Related Art

Currently, in a known trampoline, elasticity of trampoline fabric is unchangeable.

SUMMARY

To provide a user with an exercise experience of a variety of elasticity, the present invention provides a technical solution that implements adjustable elasticity of a trampoline.

The technical solution used in the present invention is that the present invention includes several corresponding trampoline ring parts, and adjacent trampoline ring parts are connected through a joint to form the trampoline; and

an arc length between the adjacent trampoline ring parts changes through adjustment of the joint, and is fixed after relative positions of the two adjacent trampoline ring parts are properly adjusted.

The joint is T-shaped, and includes a column and a connecting tube that connects the adjacent trampoline ring parts;

a through hole for a connecting rod to pass through is provided on the column in a transverse direction, and positioning parts that are located on two sides of the through hole and position the connecting rod are provided on the connecting rod; and

joint end portions of the adjacent trampoline ring parts extend downwardly to form connecting bases corresponding to the connecting rod, a connecting hole for the connecting rod to pass through is provided on each connecting base, and a position of the connecting rod on the connecting hole is adjustable and fixed.

Each positioning part has a structural form of a knob, and the positioning part is screwed into the connecting rod, and implements positioning of the connecting rod by using a threaded hole that is provided on the connecting rod and a cross bolt that passes through the knob positioning part.

Negatively provided external threads are provided at two ends of the connecting rod, and corresponding internal threads are provided at the connecting holes of the connecting bases.

Another structural form is that the joint includes a connecting tube corresponding to the trampoline ring parts, and check rings are sleeved over the connecting tube and are positioned by a stepped surface formed on the connecting tube, to change a depth at which the connecting tube enters the trampoline ring parts.

The joint has a pseudo-elliptical shape, a triangular shape, a quadrangular shape, a pentagonal shape, and a hexagonal shape, and each check ring correspondingly has a pseudo-elliptical shape, a triangular shape, a quadrangular shape, a pentagonal shape, and a hexagonal shape.

An outer edge of the check ring has a circular shape that is consistent with a circular shape of a cross section of the trampoline ring part.

2

An advantage of the present invention is that the elasticity of the trampoline is adjustable, thereby providing a user with an exercise experience of a variety of elasticity.

5 BRIEF DESCRIPTION OF THE DRAWINGS

FIG. 1 is a schematic structural diagram showing that trampoline ring parts in one structural form are assembled according to the present invention;

10 FIG. 2 is an enlarged view of a portion A in FIG. 1;

FIG. 3 is a schematic structural diagram when trampoline ring parts of the present invention are disassembled;

FIG. 4 is an enlarged view of a portion B in FIG. 3;

15 FIG. 5 is a schematic structural diagram showing that trampoline ring parts in another structural form are assembled according to the present invention;

FIG. 6 is an enlarged view of a portion C in FIG. 5;

20 FIG. 7 is a schematic structural diagram when trampoline ring parts of the present invention are disassembled;

FIG. 8 is an enlarged view of a portion D in FIG. 7;

25 FIG. 9 is a schematic structural diagram when circular pipes are assembled;

FIG. 10 is a schematic structural diagram when trampoline ring parts being circular pipes are disassembled; and

30 FIG. 11 to FIG. 20 are sectional views of check rings in different structural forms of the present invention.

In the drawings, 1 represents a trampoline ring part, 2 represents a joint, 3 represents a connecting rod, 4 represents a positioning part, 5 represents a connecting base, 6 represents a cross bolt, and 7 represents a check ring;

21 represents a column, 22 represents a connecting tube, 31 represents a threaded hole, and 51 represents a connecting hole; and

35 211 represents a through hole.

DETAILED DESCRIPTION

Embodiment 1

40 The present invention includes several corresponding trampoline ring parts 1, and adjacent trampoline ring parts 1 are connected through a joint 2 to form the trampoline.

An arc length between the adjacent trampoline ring parts 45 1 changes through adjustment of the joint 2, and is fixed after relative positions of the two adjacent trampoline ring parts 1 are properly adjusted.

The joint 2 is T-shaped, and includes a column 21 and a connecting tube 22 that connects the adjacent trampoline ring parts 1;

50 a through hole 211 for a connecting rod 3 to pass through is provided on the column 21 in a transverse direction, and positioning parts 4 that are located on two sides of the through hole 211 and position the connecting rod 3 are 55 provided on the connecting rod 3; and

joint end portions of the adjacent trampoline ring parts 1 extend downwardly to form connecting bases 5 corresponding to the connecting rod 3, a connecting hole 51 for the connecting rod 3 to pass through is provided on each connecting base 5, and a position of the connecting rod 3 on the connecting hole 51 is adjustable and fixed.

56 Each positioning part 4 has a structural form of a knob, and the positioning part 4 is screwed into the connecting rod 3, and implements positioning of the connecting rod 3 by using a threaded hole 31 that is provided on the connecting rod 3 and a cross bolt 6 that passes through the knob positioning part 4.

Negatively provided external threads are provided at two ends of the connecting rod 3, and corresponding internal threads are provided at the connecting holes of the connecting bases 5.

An adjustment process of the present invention is that the trampoline ring parts 1 are in a multi-section sleeve structure and include six sections, and the trampoline ring parts 1 are sleeved together through six corresponding joints 2 to form the trampoline. The connecting rod 3 is inserted into the through hole 211 of the column 21, and is then inserted into a connecting hole 51 on a left side. A threaded hole 31 is provided at a shaft of the connecting rod 3, and each knob positioning part 4 is fixed on the connecting rod 3 through a cross bolt 6. Nuts are provided on the connecting bases 5. A positive nut on a left side has positive threads, and a negative nut on a right side has negative threads. On the shaft of the connecting rod 3, positive threads are provided on a left side and negative threads are on provided a right side, and the threads on the left side and the right side are respectively screwed into corresponding nuts.

Embodiment 2

The present invention includes several corresponding trampoline ring parts 1, and adjacent trampoline ring parts 1 are connected through a joint 2 to form the trampoline.

An arc length between the adjacent trampoline ring parts 1 changes through adjustment of the joint 2, and is fixed after relative positions of the two adjacent trampoline ring parts 1 are properly adjusted.

The joint 2 includes a connecting tube 22 corresponding to the trampoline ring parts 1, and check rings 7 are sleeved over the connecting tube 22 and are positioned by a stepped surface formed on the connecting tube 22, to change a depth at which the connecting tube 22 enters the trampoline ring parts 1.

An adjustment process of the present invention is that the trampoline has a multi-section sleeve structure and includes six sections, and the trampoline ring parts 1 are sleeved together through six corresponding joints 2. The check rings 7 are selectively disposed at the six joints 2 to change the size of a trampoline ring. If no check ring 7 is disposed, the size of the trampoline ring is minimal. The size of the trampoline, the tightness of trampoline fabric, and elasticity are adjusted by changing a quantity of used check rings 7 or changing the length of each check ring. The check ring 7 is made of a metal pipe, or is made by means of metal die casting, or is made by means of plastic injection molding.

Each trampoline ring part 1 of the present invention may be a square pipe. Correspondingly, the connecting tube 22 and the check ring 7 may be square pipes for fitting.

Each trampoline ring part 1 of the present invention may further be a circular pipe. Freedom of a rotational direction at a sleeve joint of the circular pipe needs to be restricted to maintain the stability of the trampoline. Therefore, the joint 2 generally has a pseudo-elliptical shape, a triangular shape, a quadrangular shape, a pentagonal shape, a hexagonal shape, and the like. Correspondingly, each check ring correspondingly has a pseudo-elliptical shape, a triangular shape, a quadrangular shape, a pentagonal shape, a hexagonal shape, and the like. Certainly, an outer edge of the check ring 7 having each shape may have a circular shape that is consistent with a circular shape of a cross section of the trampoline ring part 1.

Finally, it should be noted that during the adjustment of the present invention, the joint 2 is mainly adjusted to change the relative positions of the adjacent trampoline ring parts 1 (elastic deformation of the trampoline ring parts may be ignored here) to change the size of a trampoline ring (a primary factor). Moreover, because a particular elastic deformation inevitably occurs during adjustment of the trampoline ring parts 1, the size and elasticity of the trampoline ring also changes (a secondary factor). Therefore, an adjustment effect of the trampoline ring of the present invention is achieved by combining the primary factor with the secondary factor.

What is claimed is:

1. A trampoline with adjustable elasticity, wherein the trampoline comprises several corresponding trampoline ring parts, and adjacent trampoline ring parts are connected through a joint to form the trampoline; and

an arc length between the adjacent trampoline ring parts changes through adjustment of the joint, and is fixed after relative positions of the two adjacent trampoline ring parts are properly adjusted, wherein:

the joint is T-shaped, and comprises a column and a connecting tube that connects the adjacent trampoline ring parts;

a through hole for a connecting rod to pass through is provided on the column in a transverse direction, and positioning parts that are located on two sides of the through hole and position the connecting rod are provided on the connecting rod; and

joint end portions of the adjacent trampoline ring parts extend downwardly to form connecting bases corresponding to the connecting rod, a connecting hole for the connecting rod to pass through is provided on each connecting base, and a position of the connecting rod on the connecting hole is adjustable and fixed.

2. The trampoline with adjustable elasticity according to claim 1, wherein each positioning part has a structural form of a knob, and the positioning part is screwed into the connecting rod, and implements positioning of the connecting rod by using a threaded hole that is provided on the connecting rod and a cross bolt that passes through the knob positioning part.

3. The trampoline with adjustable elasticity according to claim 1, wherein negatively provided external threads are provided at two ends of the connecting rod, and corresponding internal threads are provided at the connecting holes of the connecting bases.

4. The trampoline with adjustable elasticity according to claim 1, wherein the joint comprises a connecting tube corresponding to the trampoline ring parts, and check rings are sleeved over the connecting tube and are positioned by a stepped surface formed on the connecting tube, to change a depth at which the connecting tube enters the trampoline ring parts.

5. The trampoline with adjustable elasticity according to claim 4, wherein the joint has a pseudo-elliptical shape, a triangular shape, a quadrangular shape, a pentagonal shape, or a hexagonal shape, and each check ring correspondingly has a pseudo-elliptical shape, a triangular shape, a quadrangular shape, a pentagonal shape, or a hexagonal shape.

6. The trampoline with adjustable elasticity according to claim 5, wherein an outer edge of the check ring has a circular shape that is consistent with a circular shape of a cross section of the trampoline ring part.
